INSULATED PICNIC CHEST

Robert A. White, Cleveland Heights, Ohio, assignor to
The Hamilton-Skotch Corporation, Cleveland, Ohio

Filed Sept. 8, 1970, Ser. No. 24,864

Term of patent 14 years

Int. Cl. D7—99

U.S. Cl. D44—1

FIG. 1

FIG. 2

FIG. 3

FIG. 4

FIG. 1 is a top plan view of an insulated picnic chest showing my new design;

FIG. 2 is a front elevational view.

FIG. 3 is a left side elevational view; and
FIG. 4 is a rear elevational view.

I claim:

The ornamental design for an insulated picnic chest, substantially as shown.
